UNITED STATES PATENT OFFICE.

FREDERICK LINDNER, OF CHICAGO, ILLINOIS.

DEVICE FOR HOLDING WATCHES.

No. 890,145.

Specification of Letters Patent.

Patented June 9, 1908.

Application filed September 13, 1907. Serial No. 392,753.

To all whom it may concern:

Be it known that I, FREDERICK LINDNER, a citizen of the United States, residing at Chicago, in the county of Cook and State of Illinois, have invented new and useful Improvements in Devices for Holding Watches, of which the following is a specification.

This invention relates to safety attachments for watches, and one of the principal 10 objects of the same is to provide means whereby a watch may be securely held in a pocket so that it can not be surreptitiously withdrawn or from which the watch will not drop in changing the clothing.

15 Another object of the invention is to provide a simple clasp having a spring hook formed thereon or connected thereto in which the ring of a watch is to be connected, said clasp being attached to the outer wall 20 upon the inside of a pocket in position to permit the watch to be readily withdrawn and connected to the clasp.

25 These and other objects may be attained by means of the construction illustrated in the accompanying drawing, in which:

Figure 1 is a side elevation of a portion of a garment having a pocket secured thereto and showing my safety attachment and a watch connected thereto in dotted lines. Fig. 2 is a 30 vertical section taken through the pocket and showing a watch connected to the clasp. Fig. 3 is a perspective view of the safety clasp showing a watch, said clasp being detached from the pocket.

35 Referring to the drawing for a more particular description of my invention, the numeral 1 designates the portion of a garment to which a pocket 2 is secured and 3 is the edge band of the pocket. Secured to the 40 band 3 inside the pocket is a clasp comprising a base plate 4 having suitable perforations 5 therein through which the threads for attaching the plate to the band 3 are

passed. The plate 4 is provided with a central recess or cut-away portion 6. A spring 45 tongue 7 preferably formed integral with the plate 4 extends from one end thereof and forms a loop 8 to which the watch ring 9 is connected. The tongue 7 extends from the loop 8 over the plate 4 and is provided with a 50 curved portion 10 which normally extends within the recess 6, and the terminal end 11 of the hook projects slightly beyond the plate 4 and is bent towards the plate as shown more particularly in Fig. 3. The result of this construction is that when the ring 9 is engaged with the tongue and passed from the terminal end 11 into the loop 8, the tongue is flexed or bent outward from the plate and after the ring is secured to the loop 55 8 the tongue normally presses towards the plate with the curved portion 10, seating within the recess 6, and thus prevents the withdrawal of the watch excepting by a lateral movement. 65

My invention is of simple construction, can be quickly applied to any pocket, can be manufactured at slight cost and is durable and efficient for its purpose.

Having thus described the invention, what 70 I claim as new, is:

The herein described device for holding 75 watches in pockets comprising a plate having a central cut-away portion, and a spring tongue projecting from one end of the plate and forming a loop for the watch ring, said tongue having a curved portion normally disposed within the cut-away portion, and a curved terminal end extending beyond the plate, said plate being secured inside a pocket. 80

In testimony whereof I affix my signature in presence of two witnesses.

FREDERICK LINDNER.
